[57] **CLAIM**

The ornamental design for a lipstick container with transparent dust protector, as shown and described.

DESCRIPTION

FIG. 1 is a perspective view of the design for a lipstick container with transparent dust protector;

FIG. 2 is a front elevational view thereof, the rear, right and left sides being identical to the side shown;

FIG. 3 is a top view thereof;

FIG. 4 is a bottom view thereof;

FIG. 5 is a left side elevational shown with the topshell removed in order to disclose the underlying dust cover;

FIG. 6 is a front elevational view thereof;

FIG. 7 is a rear elevational view thereof; and,

FIG. 8 is a top view thereof, shown on an enlarged scale.
